(Cl. D48—20)

To all whom it may concern:

Be it known that we, Joseph Dern and Joseph H. Harris, citizens of the United States, residing at Roxbury and Brookline, in the counties of Suffolk and Norfolk, respectively, and State of Massachusetts, have invented a new, original, and ornamental Design for a Combined Telephone Stand and Lamp, of which the following is a specification, reference being had to the accompanying drawing, forming part thereof.

Figure 1 is a perspective view of a combined telephone stand and lamp, showing our new design, and

Figure 2 is a fragmentary side elevational view thereof.

We claim:

The ornamental design for a combined telephone stand and lamp, as shown,

JOSEPH DERN.

JOSEPH H. HARRIS.
